UNITED STATES PATENT OFFICE.

JOSEPH WILLIAM FAY, OF MILWAUKEE, WISCONSIN.

KEY.

Application filed February 14, 1919, Serial No. 277,005. Renewed April 16, 1920. Serial No. 374,491.

To all whom it may concern:

Be it known that I, JOSEPH WILLIAM FAY, a citizen of the United States, residing at Milwaukee, in the county of Milwaukee and 5 State of Wisconsin, have invented new and useful Improvements in Keys, of which the following is a specification.

This invention relates to an improvement in keys and the principal object of the invention is to provide a key with detachable means for indicating the room or building to which the key belongs.

The invention consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a front view of the invention. 25 Figure 2 is a section on line 2—2 of Figure 1.

Figure 3 is a section at right angles to Figure 2.

In these views 1 indicates the shank of 30 the key, and 2 indicates the head thereof which is provided with the usual opening 3 for receiving the key ring. In carrying out my invention I form a recess 4 in one face of the head of the key immediately below said opening. As clearly shown in the drawings, this recess is of oblong shape with rounded ends and of sufficient depth to receive the plate 5 of cardboard or the like on which is inscribed the name of the 35 room or building for which the key is used and also a cover plate 6 of glass or celluloid or other transparent material. The cardboard plate on its reverse side may also present the name of the owner so that if 40 the key is lost the owner may be found by removing the plate and thus disclose the name of the owner. The cardboard plate is simply dropped into the recess and the transparent plate placed therein on top of 45 the cardboard plate. This transparent plate is so made that it will have a tight fit in the recess and be held therein by friction. The

said transparent plate is made of less length than the recess so that a pin may be passed under the end of the plate to remove the 55 same.

I treat the paper plate or the celluloid plate with radium or phosphorus or some other illuminating substance so as to make it possible to locate the desired key at 60 night or in the dark.

It is thought from the foregoing description that the advantages and novel features of my invention will be readily apparent.

I desire it to be understood that I may 65 make changes in the construction and in the combination and arrangement of the several parts, provided that such changes fall within the scope of the appended claims, by discerning the inscription on the plate. 70

What I claim is:—

1. As an article of manufacture, a key having a recess in its head of oblong shape with rounded ends, a name plate loosely fitting in said recess and a cover plate frictionally held in said recess above the name plate and of less length than said recess whereby a space is left for the introduction of removing means for said plate. 75

2. As an article of manufacture, a key having its head provided with a recess in which is placed a name plate, and a transparent cover for the said plate frictionally held in the recess, with a space reserved between the cover and the wall of the recess, 80 for the insertion of removing means. 85

3. As a new article of manufacture, a key having a recess in its head, and a name plate in said recess, said name plate being treated with an illuminating substance, and a transparent cover for the said plate also inserted in the said recess and frictionally held in place by engagement of the cover with the walls thereof. 90

4. As an article of manufacture, a key having a recess in its head, an illuminating name plate in said recess, and a transparent cover for the said plate frictionally held in the recess, with an open space between the cover and the wall of the recess for the 100 insertion of removing means.

In testimony whereof I affix my signature.

JOSEPH WILLIAM FAY.
